UNITED STATES PATENT OFFICE.

ATWOOD L. BOGGS, OF STOUGHTON, MASSACHUSETTS.

DISPENSING APPARATUS.

Application filed September 13, 1926. Serial No. 135,106.

This invention relates to an improvement in a dispensing apparatus being directed more particularly to a water cooler, of the so-called inverted water bottle type, which is provided with means for agitating the liquid in the cooler receptacle periodically as the outlet spigot is operated for drawing off the cooled cooler contents.

The primary object of the present invention is the provision of an agitator for liquid dispensing devices.

A further object of the invention is the provision of a motor driven agitator for liquid dispensing devices constructed in a manner whereby the operation of the agitator is automatically started and stopped periodically as the outlet spigot of the cooler is operated.

A further object of the invention is the provision of a device of the character described which is neat in appearance, cheap and simple of construction and manufacture, and highly efficient in operation.

A further object of the invention is the provision of a novel means for locking the agitator motor against running and releasing the motor for operation as desired.

Further novel features of construction and improved results of the invention will appear from the following description and in the accompanying drawings.

In the drawings:

Figure 1 is a view in side elevation of a cooler provided with the improved invention.

Figure 2 is a front view of the driving motor for the agitator.

Figure 3 is a fragmentary enlarged vertical sectional view showing the application of the invention to a cooler.

Figure 4 is an enlarged detail perspective view of the motor locking and releasing device.

Figure 5 is a fragmentary enlarged vertical sectional view of the cooler embodying a modified form of the invention.

At the present time it is the common practice to sell at drug store fountains and like places cooled drinks which may be made from the pulp of different fruits.

In the liquid forming these drinks there is present a large portion of the pulp of the fruit from which the drinks are made and it has been found advisable to agitate this liquid from time to time.

Where these drinks are contained in and

dispensed from a liquid cooler, it is additionally advisable and highly desirable to agitate the liquid periodically to prevent clogging of the cooler container outlet in addition to agitating the liquid for the purpose of keeping it properly mixed.

Having the above in mind the present invention has been conceived and comprises in broad terms a cooler A having an ice chamber B, a liquid container C, an outlet spigot D, an agitator E and a driving motor F for rotating the agitator. The motor locking and releasing member is designated at G.

Describing the invention in detail, it will be seen that the liquid container C is carried concentrically within the ice chamber B of the cooler and that the liquid from the container passes outwardly through the pipe 10 to the spigot D, the spigot D being provided with a reciprocating valve operating plug or button 11. Suitable packing 12 is provided at the inner end of the pipe 10 where it penetrates the container C. An additional packing 13 and 14 is provided at the inner and outer sides of the outer cooler wall 15 where the pipe 10 passes outwardly through this wall.

The agitator comprises a horizontally mounted propeller E composed of a plurality of blades 16, this propeller being positioned in the container C and carried by the horizontal shaft 17, the outer end 18 of which has connection with the driving motor F.

At the point where the shaft passes through the walls of the container C and the outer wall 15 of the cooler, suitable packing arrangement is provided in the form of screw threadably mounted and adjustable members 19 which are adapted to exert an adjustable pressure against the packing 20.

In the form of invention appearing in the drawings, the agitator driving motor F is in the form of a spring clock mounted and suitably supported upon brackets 21 on the outer face of the cooler at a point just above the spigot D. For the purpose of lending a pleasing appearance to the device, the motor is provided with a casing or cover 22. The spring 23 of the motor is wound from time to time through the medium of the handle 24.

The propeller shaft 17 is not driven directly off the spring 23 but is driven through

a chain of gears 25, 26 and 27, the gear 27 being connected directly with the inner end of the propeller shaft.

The motor locking and releasing device 5 G comprises a rod having a vertical portion 28 attached to the valve operating button 11 and a horizontal portion 29, the inner end of which is flattened and enlarged as at 30, and is adapted to reciprocate through a suitable opening in the rear frame 31 of the clock works. A reduced portion 32 of this member passes inwardly and through a suitable opening 33 in the housing and through another suitable opening 34 in the front frame member 35 of the clock works. Intermediate the reduced portion 32 and the enlarged inner end portion 30 the rod is provided with an upwardly extending knife edge 36 which edge is adapted to normally engage the gear teeth 37 of the motor gear 25.

It will be seen, however, that whenever the valve operating button 11 is pushed inwardly for withdrawing liquid from the cooler 25 container, that the knife edge 36 of the motor locking member is carried inwardly and out of engagement with the teeth of the gear 35, thus permitting the clock spring to start the rotation of the gears and consequently 30 whirl the agitator propeller E, thus causing an agitation of the liquid in the container.

It will be readily understood that the clock spring can be of a size so that when once wound it will have sufficient strength to 35 continue to rotate the agitator propeller until a given amount of liquid has been withdrawn from the cooler.

It will further be readily understood that 40 an electric motor or other suitable power means could be substituted for the clock works without departing from the spirit of the invention.

The particular form of cooler shown in 45 Figure 1 of the drawings is that known as the inverted water bottle type, the main liquid supply being carried by the bottle 38 which is inverted upon the upper end of the cooler, the neck of the bottle extending downwardly through the opening 39 which 50 comprises the upper end of the container C. The cooler is provided with a cover 40 provided with a door 41 whereby ice can be inserted into the ice chamber B. As is common in coolers of this character, a spigot 42 55 is provided for draining the liquid from the ice chamber of the cooler into the overflow tray 43. The cooler can be supported upon any suitable stand 44 or the like.

In a device of this character it is advisable 60 to have as little metal as possible in the liquid container C and from the drawings and description it will be seen that in the preferred form of the invention the only metal in this container is the inner end of 65 the shaft 17 and the agitator propeller E.

Referring now to Figure 5 of the drawings it will be seen that the main difference in construction appears to be the manner of locking and releasing the driving motor.

In the form of the invention the cooler 70 construction is exactly similar to that appearing in the preferred form and the same motor construction is also used.

The shaft 17 is provided with the packing 75 20 and adjustable packing nut 19 at the point where the shaft passes through the outer wall 15 of the cooler. The packing construction at the point where the shaft passes through the wall of the container C is slightly different. In this instance the 80 adjustable packing nut 19 is screw threaded in the elongated bearing 40, which bearing is in turn screw threadably mounted in an opening through the side of the container. To prevent leakage through the 85 opening in the container wall, additional packing is provided in the form of internal and external washers 41 and a nut 42.

A gear 43 fastened at 44 so as to rotate with the shaft 17 is positioned on the shaft 90 intermediate the propeller and the inner end of the elongated bearing 40. The valve operating button 11 is provided with a rod 45 which extends through the outlet pipe 10 and is adapted to reciprocate upon the movement of the valve button. Mounted upon the inner end of this rod is an upwardly extending guide member 46, the upper end of which is provided with an opening 47 through which the shaft 17 passes. Intermediate its length the guide member 46 is provided with a tapered knife blade 48 which blade, when the valve is in a closed position, engages the teeth of the propeller shaft gear 43, thereby locking the motor 95 and shaft against rotation.

A second guide member 49 is fastened through the medium of a nut 50 against the packing nut 12. This guide member has a forked horizontal portion 51 which extends 110 parallel to the shaft 17 intermediate the shaft and the valve rod 45. The knife blade 48 is adapted for reciprocation within the forked end 51 of the guide 49 to prevent rocking motion of the blade.

By reason of the two guides 46 and 49, the knife blade will reciprocate in a predetermined vertical plane so as to always properly engage with and be easily disengaged from teeth of the propeller gear wheel 43.

It will be readily apparent that as the valve operating button 11 is pushed inwardly to draw liquid from the container C, that the knife blade 48 will be moved inwardly sufficiently far to become disengaged with 125 the gear 43, thus to permit the motor to whirl the propeller valve and bring about an agitation of the liquid in the cooling container C.

Having thus described my invention, what 130

I claim and desire to secure by Letters Patent is:

1. In combination with a liquid cooler, a propeller agitator for the liquid, said propeller mounted upon a horizontal shaft having connection externally of the cooler with a motor, a valve positioned adjacent said motor for controlling the withdrawal of liquid from the cooler, and a lock bar carried by said valve and having connection with the said motor for locking it against running, whereby said lock bar is moved out of engagement with the motor when the valve is moved to an open position.
2. A liquid cooling and dispensing apparatus, comprising a container for the liquid, a reciprocating valve for controlling the discharge of liquid from the container, a propeller agitator arranged in said container, and mounted upon a horizontal shaft having external connection with a motor, a gear mounted on said shaft in said container, said valve having a rod extending into the container beneath said shaft, a lock carried by said valve shaft and normally

having locking engagement with the teeth of said gear, and said lock adapted to be moved out of engagement with the propeller shaft gear when the valve is opened, whereby the motor actuates the propeller when liquid is being drawn from the container. 30

3. An apparatus for dispensing liquids comprising a container for the liquid, a draw-off valve, an agitator mounted upon a horizontal shaft and connected to a motor, a lock member carried by the valve and in engagement with the motor for locking the motor against running when the valve is in closed position. 35

4. An apparatus for dispensing liquids 40 comprising a container for the liquid, a draw-off valve, a shaft in the container, an agitator on said shaft, a motor for driving the shaft, a gear on the shaft, and means carried by the valve engaging the gear for 45 locking the motor against running when the valve is in closed position.

In testimony whereof I hereunto affix my signature.

ATWOOD L. BOGGS.
